(57) CLAIM

The ornamental design for a footwear as shown and described.

DESCRIPTION

FIG. 1 is a perspective view taken from the top, front, right of a footwear embodying the new design;

FIG. 2 is a perspective view taken from the bottom, front, left thereof;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a rear view thereof.

The features shown with dot-dot-dash broken lines in the figures form no part of the claimed design. The heavier dash-dash broken lines represent stitching, which forms a part of the claimed design.
